(57) **CLAIM**

The ornamental design for an accessory case, as shown and described.

DESCRIPTION

FIG. 1 is a perspective view of an accessory case showing my new design;

FIG. 2 is a front view thereof, the rear view being an identical image;

FIG. 3 is a right side view thereof, the left view being an identical image;

FIG. 4 is a top view thereof;

FIG. 5 is a bottom view thereof;

FIG. 6 is a cross-sectional view taken along line 6-6 in FIG. 2;

FIG. 7 is a perspective view thereof, showing the internal partition in an open position;

FIG. 8 is a top view thereof, showing the internal partition in the open position;

FIG. 9 is an exploded perspective view thereof; and,

FIG. 10 is an exploded perspective view thereof, shown in environmental use.

The broken lines in FIG. 6 show portions of the accessory case that form no part of the claimed design. The broken lines in FIG. 10 show the environment for illustrative purposes only and form no part of the claimed design.
